(57) **CLAIM**

We claim the ornamental design for a race car suspension cup, as shown and described.

DESCRIPTION

FIG. 1 is an elevated perspective top view of the invention; FIG. 2 is a side perspective view thereof; FIG. 3 is a bottom perspective front view thereof; FIG. 4 is an elevation view with environment thereof; and, FIG. 5 is a top perspective view with environment thereof. The broken line showing the suspension spring is provided for the purpose of illustrating environmental structure and forms no part of the claimed design.

1 Claim, 5 Drawing Sheets
